UNITED STATES PATENT OFFICE.

CHARLEY LANDGRAF AND JOHN HERNACKI, OF CHICAGO, ILLINOIS.

RECORD WIPER FOR PHONOGRAHS.

1,424,023.

Specification of Letters Patent. Patented July 25, 1922.

Application filed April 17, 1922. Serial No. 553,375.

To all whom it may concern:

Be it known that CHARLEY LANDGRAF and JOHN HERNACKI, citizens of the United States of America, residing at Chicago, in 5 the county of Cook and State of Illinois, have invented new and useful Improvements in Record Wipers for Phonographs, of which the following is a specification.

The object of the invention is to provide 10 a simple and efficient means in the form of an attachment for phonographs and similar musical and talking machines for wiping the record to remove dust from the surface thereof and particularly from the sound 15 groove as a means of preventing irregular or undesirable vibrations of the needle and protecting the sound groove from injury; and with this object in view the invention consists in a construction and combination 20 of parts of which a preferred embodiment is shown in the accompanying drawings, wherein:—

Figure 1 is a view of a wiper embodying the invention applied in the operative position to the sound arm of a conventional form 25 of phonograph.

Figure 2 is an end view of the same to show the inclination of the brush holder to correspond with that of the needle. 30 The device consists essentially of a supporting arm 10 provided with suitable means for attachment to a sound arm indicated at 11 and carrying a brush 12 of which the fibres are attached to a body portion consisting 35 of a plate 13 arranged in contact with the supporting arm and disposed by reason of the transverse inclination or oblique position of the latter at an inclination to the plane of the record which corresponds 40 approximately with the inclination of the needle and which, therefore, is adapted to drag or wipe the fibres along the surface of the record as it is rotated to effectually remove any dust or foreign matter from the sound 45 groove.

In the construction illustrated the supporting arm consists of a flat strip of metal twisted at 14 to provide for the transverse inclination of that portion to which the brush is attached and which is longitudinally slotted as indicated at 15 for the reception of a set screw 16 which serves to secure the body portion of the brush in place in a position best suited to effect the desired object and to adapt the brush to be adjusted 50 to suit the construction of the phonograph. Furthermore the plate 13 forming the body

portion of the brush is slotted as indicated at 17 also for engagement by said set screw 16 to provide for adjustment of the brush toward and from the plane of the record to 60 insure an efficient operation thereof.

The means illustrated in the drawing for attaching the brush supporting arm to the sound arm of the phonograph consists of a clamp 18 having a jaw 19 which may be 65 formed as a continuation of the shank of the supporting arm and a jaw 20 movable toward and from the jaw 19 and adjustable by means of a clamping screw 21 or the equivalent thereof, the shank of the jaw 20 70 having a terminal fulcruming point 22 for bearing the contact with the shank of the supporting arm.

It will be obvious that the device can be 75 readily applied to any of the ordinary or commercial forms of phonographs in a position to precede the sound box needle in traversing the sound groove so as to remove any particles of dust or foreign matter which may have accumulated in the groove to insure 80 a proper reproduction of the record.

Having described the invention, what is claimed as new and useful is:—

1. A record wiper for phonographs and similar machines having a supporting arm 85 provided with means for engagement with a phonograph sound arm, and a brush having a body portion consisting of a plate arranged in contact with said arm and adjustably mounted thereon for arrangement in 90 advance of the sound box needle, the supporting arm having a longitudinal slot and the body portion of the brush being provided with a corresponding slot extending at right angles thereto for mutual engagement by a set screw to provide for adjustment of the brush in directions parallel with and transverse to the length of the supporting arm. 95

2. A record wiper for phonographs and similar machines having a supporting arm provided with means for engagement with a phonograph sound arm, and a brush carried by and connecting with said supporting arm by a single attaching means whereby 100 the brush may be adjusted both towards and away from the record or longitudinally of said supporting arm or both. 105

In testimony whereof they affix their signatures.

CHARLEY LANDGRAF.
JOHN HERNACKI.
